LUBRICATING PAD

Morris Keys, Chicago, Ill.

Application February 26, 1936, Serial No. 64,313

1 Claim. (Cl. 308—88)

This invention relates to lubricating pads.

It is an object of this invention to provide an improved lubricating pad which is relatively simple and inexpensive in construction and efficient in use.

Another object of the present invention is to provide a new and improved pad for lubricating the journals of railway cars and the like.

A further object of the present invention is to construct the new lubricating pad in such a manner that the same will always be in distended position so as to positively engage and effectively lubricate the journal or other bearing surface with which the new lubricating pad is associated.

15 Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a view, partly in section and partly in elevation, showing a preferred form of the present invention in use;

25 Fig. 2 is a transverse sectional view on line 2—2 in Fig. 1;

Fig. 3 is a perspective view showing a preferred form of the new lubricating pad; and

30 Fig. 4 is a plan view of the same.

A preferred form of the new lubricating pad is shown in the drawing, is therein generally indicated at 10, and comprises an outer casing 11, which may be made of fabric or any other porous flexible material. Provided in this casing 11, on the upper side thereof, is a centrally disposed opening 14. Arranged in the casing 11, and inserted thereinto through the opening 14 therein, is a body of oil-absorbent material 12 which may be, for example, felt or other analogous and equivalent oil-absorbent material, and arranged in the casing 11, at suitable intervals therein, are normally distended coil springs 13.

The new lubricating pad is shown, for the purpose of illustrating its use in connection with a typical bearing surface, as being used in conjunction with the journal 15 of a railway car, the journal box being indicated at 16 and having a door 17 which is hinged thereto, as at 18, and through which the lubricating pad 10 may be inserted into the journal box.

In the use of the new lubricating pad the oil-absorbent body 12 of the same may be saturated

with oil before being inserted into the casing 11 or the body 12 may be saturated with lubricating oil by pouring the latter into the absorbent body 12 of the pad through the central opening 14 in the casing 11, whereupon the pad may be inserted into the journal box 16 through the door 17, the pad being arranged, when in use, between the bottom wall 19 of the journal box and the journal 15. When the pad is thus disposed in position of use the coil springs 13 urge the oil-bearing pad 10 into engagement with the peripheral surface of the journal 15, thereby effectively lubricating the latter. It is to be noted, in this connection, that the springs 13, being normally distended, bear the upper surface of the pad 10 against the journal 15 and prevent the pad from falling or sagging away from the journal when in use, which is an objectionable feature of the usual type of loose waste oil absorbent material now used for lubricating the journals of railway cars and the like.

It is to be noted that the pad 10 may, if desired, be inserted into the journal box 16 and the oil then poured onto the pad 10 through the opened door 17 of the journal box 11.

While the new lubricating pad 10 has been shown as being used in connection with the journals of railway cars, it is understood that the new pad is not limited to this use but may be used in conjunction with various other bearing surfaces which it is desired to lubricate.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

A lubricating pad comprising a flexible casing, a body of oil-absorbent material in the said casing, and springs in the said casing for distending the said casing so as to urge the outer surface thereof into bearing contact with a surface to be lubricated by the said pad, said casing having an opening formed therein, in the upper side thereof, through which lubricating oil may be poured into the said oil-absorbent body therein.

MORRIS KEYS.
